UNITED STATES PATENT OFFICE.

JAMES A. ST. JOHN, OF ST. LOUIS, MISSOURI.

DESIGN FOR TYPE.

SPECIFICATION forming part of Design No. 13,729, dated March 13, 1883.

Application filed November 27, 1882. Term of patent 3½ years.

To all whom it may concern:

Be it known that I, JAMES A. ST. JOHN, a subject of the Queen of Great Britain, residing in the city of St. Louis, Missouri, have invented and produced a new and original Design for Movable Type, of which the following is a specification, reference being had to the accompanying impression, forming part thereof.

The characteristics of the present font of type are, first, the hair-line *c* in the letters *E* and *F*; second, the termination of the numerals 1 and 4, as shown at *f*; third, the combination of the above-named characteristics in a font of movable type, as shown in the accompanying fac-simile.

I claim—

1. The design for movable type herein shown and described, the same consisting in the curved and extended line *c* in the letters *E* and *F*.
2. The design for movable type herein shown and described, the same consisting in the termination *f* of the numerals 1 and 4.
3. The design for movable type herein shown and described, the same consisting, in combination, of the heavy and light outline, the hair-line termination at the top of the letters, the points *a*, the curved and extended line *b*, the line *c*, and the light angled line *d*.

JAMES A. ST. JOHN.
